HIGH CONVERGENCE ELECTRON GUN WITH
MAGNETICALLY SHIELDED CATHODE
Donovan V. Geppert, Sunnyvale, Calif., assignor to Sylvania Electric Products Inc., a corporation of Delaware
Filed Nov. 17, 1961, Ser. No. 152,985
3 Claims. (Cl. 313—84)

This invention relates to electron guns and more particularly to the forming and shaping of emitted electrons into a high density beam of small diameter.

Two widely used techniques for producing and confining electron beams in traveling wave tubes are known as the "confined flow" and "Brillouin flow" systems. In the "confined flow" operation, electrons comprising the beam are immersed in a strong longitudinal magnetic field provided by a solenoid or permanent magnet. This type of flow is generally produced by a plane-type emitter (flat emitting surface) and the current density of the resultant beam, which is a measure of the power of the tube, is equal to that of the emitter.

In the "Brillouin flow" system a cathode with a concave emitting surface is used to produce electrons which are accelerated and formed into a converging beam by a set of focusing electrodes. That is, the diameter of the beam is progressively reduced as it travels toward the start of the slow wave structure of the tube. In a plane beyond the last gun electrode, the beam achieves a minimum diameter; at which time it is abruptly introduced into an axially oriented magnetic field. For convenience, the term "abruptly" is used to indicate the entrance condition encountered by the beam in passing from a region free of external fields to one having a magnetic field in the axial direction only. (See L. Brillouin, "A Theorem of Larmor and Its Importance for Electrons in Magnetic Fields," Physical Review, volume 67, No. 7 and 8, April 1 and 15, 1945.)

Although higher density beams are obtainable from a concave emitter than from a plane emitter of the same diameter, the former involves a problem that the amount of convergence of the beam, and hence electron density, directly relates to the focusing characteristics of the electron gun. More particularly, the amount of convergence of the beam depends upon the magnitude and orientation of the electrostatic fields provided by the focusing electrodes. Additional convergence by inward focusing forces derived from the interaction of the electrons comprising the beam with a gradually increasing magnetic field has not been used because of the unpredictable relationship between the diameter of the electron beam and the magnetic field in the region where the latter is increasing.

In accordance with the invention, Brillouin focused electron beams of small diameter are achieved by providing a gradually increasing axial magnetic field in the region between the gun structure and the commencement of the slow wave structure. Inward focusing forces derived from the interaction of the electrons of the beam with the longitudinal component of the field continue the convergence initiated by the electrostatic forces of the focusing electrodes causing the radius of the electron beam to decrease exponentially in the direction of electron flow to a value which sustains Brillouin flow. The increasing field is an ancillary portion of the longitudinal magnetic fields produced by an electromagnetic focusing solenoid surrounding the beam and is provided by a cylindrically shaped pole piece extension or hub attached to and integral with an end of the solenoid.

It is therefore an object of the invention to provide an improved electron gun for traveling wave tubes wherein electron beams of high current densities in Brillouin flow are realized.

Another object is to provide an electron gun having a

2

spherically shaped cathode for production of small diameter beams wherein Brillouin flow is achieved.

A still further object of the invention is to provide an apparatus for producing in conjunction with a converging electron beam, a converging magnetic field which permits the beam to be focused to a small diameter which sustains Brillouin flow.

A still further object is to provide means for producing, in conjunction with a converging electron beam provided by an electron gun having a limited number of focusing electrodes, a controlled, gradually increasing magnetic field in the direction of beam travel which permits the beam to be focused to a small diameter which sustains Brillouin flow.

The above-mentioned objects and features of the invention will be more clearly understood from the following detailed description when read in conjunction with the drawings in which:

FIGURE 1 is a plan view, partially in cross-section and broken near each end, of a traveling wave tube and an electromagnetic solenoid illustrating the electron gun and the magnetic field shaping pole piece of the solenoid;

FIGURE 2 is a transverse section of the pole piece of the solenoid taken along line 2—2 of FIGURE 1;

FIGURE 3 is an enlarged perspective view of the pole piece taken along line 3—3 of FIGURE 1 illustrating the path of an electron within the pole piece under the influence of a beam-controlling magnetic field;

FIGURE 4 is a normalized plot of axial magnetic field strength of the solenoid as a function of location along its axis of symmetry comparing the magnetic field build-up curves of the prior art and that of the present invention;

FIGURE 5 is an enlarged view of the field shaping pole piece of the solenoid of FIGURE 1, partially broken away, and illustrates the distribution of a portion of the flux density of the magnetic field about the axis A—A of the assembly, and

FIGURE 6 is a partially schematic view of the electron gun structure of the device shown in FIGURE 1 and illustrates the trajectories of a few of the electrons of the beam in the region between the cathode and the ordinate points S and T on the axis of beam travel.

Referring to FIGURE 1, a traveling wave tube generally indicated at 10 is provided with an external magnetic circuit, such as an electromagnetic solenoid 11, suitably positioned relative to the central region of the tube and extending parallel with the longitudinal axis A—A of the former. The solenoid 11 consists of layers of wire, generally indicated at 12, electrically isolated from one another, wound about a centrally disposed tubular member 13, the walls of which define an envelope into which the tube 10 is located. An elongated cylindrical shell 14 protects the windings 12 from foreign matter and the like, and is mounted to annular pole pieces 16 and 17 located at respective ends of the member 13.

When an appropriate energizing potential is applied to the winding, as by leads 18 protruding through pole piece 17, a magnetic field is produced. In the region adjacent the elongated barrel 19 of the envelope (FIGURE 2), this field is coextensive with the longitudinal axis of the tube to radially contain the beam with minimum magnetic field. In the region adjacent the spherically-concave surface 20 of the cathode 21, the field is substantially zero, but increases to the right as viewed, to provide a gradually increasing magnetic field in the direction of beam travel. The relationship of the field and beam in these respective regions will be made clearer by the mathematical analysis which follows.

In order to provide rectilinear motion of the electrons emanating from the surface 20, an electrostatic field forming means, such as focus cup 23, and anode 25 is arranged

about the path of the electron beam adjacent the cathode. The focus cup 23 is formed of a cylinder having a centrally apertured end 26, located adjacent the surface 20 of the cathode by its attachment with circumferentially spaced, axially extending ceramic supports 28.

Anode 25, coaxial with longitudinal axis A—A, is comprised of cylinder 30 having a re-entrant lip 31. Axial and radial location of anode 25 relative to focus cup 23 and cathode 21 is provided by ceramic members 28 located at and permanently affixed to its peripheral edge.

The surface 20 of cathode 21, as well as focus cup 23 and anode 25, are suitably energized by outside energy sources (not shown) connected by means of leads 33 located at the end of the gun envelope. In operation, the temperature of surface 20 is increased when the heater 34 located adjacent its inner surface is energized, which causes electrons to be emitted from surface 20. On application of a positive potential (relative to cathode 21) to anode 25 and a suitable focusing potential to focusing cup 23, a field pattern forms the emitted electrons into a conically-converging beam, successive segments of which are then accelerated toward the slow wave structure of the tube.

However, this converging field pattern is derived from electrostatic forces only, a portion of which is indicated at 35 in FIGURE 6 as imaginary surfaces of equal potential formed as a result of the static charges of focus cup 23 and anode 25. In the region adjacent the cathode 21, the curvature of these surfaces matches that of the surface 20 such that the respective centers of formation are coincident at the ordinate S located on the axis of beam travel (FIGURE 6), forming a smoothly converging beam in the region between the cathode and point S. Trajectories 38 of individual electrons comprising the beam depicting the smoothly converging nature of the beam in this region are shown in FIGURE 6.

Along successive planes normal to the beam axis in this region there is no tendency for the electrons to deviate from converging paths because the potential distribution outside the beam is similar to the potential distribution existing inside the beam. Stated somewhat differently, the field forming means including the focus cup 23 and anode 25 effectively produce forces normal to the edge of the electron beam to balance the neutral space charge forces of the electrons.

Note that the field balances the space charge forces of the beam only over a finite axial distance, and that the distance depends on the number and spacing of the electrodes as well as the magnitude of the biasing voltage of the latter. This qualification has resulted in beams of small convergence being produced from electron guns having a limited number of electrodes and it is to such guns that this invention is directed.

As the beam passes the anode region, the converging effects of the electrostatic fields of the gun electrodes diminish and the space charge forces of the electrons comprising the beam become more predominant. However, these space charge forces are balanced and convergence of the beam continues owing to the fact that the beam is introduced into a gradually increasing magnetic field in the region between ordinate points S and T located on the axis of beam travel (FIGURE 5). This gradually increasing field is derived from the longitudinal magnetic field provided in the central region of solenoid 11, the shape of the field being dependent upon the shape and properties of magnetic flux shaping hub 40 extending from and integral with the pole piece 16 of the solenoid 11. The reasons for the convergence of the beam can be best explained with references to FIGURES 3 and 5.

When a voltage is applied to the windings of solenoid 11, a magnetic field is produced along the longitudinal axis of the tube. Owing to the aperture between the planes of surfaces 52 and 53 of the pole piece 16 of the solenoid 11, a fringing field is also created, the axial dis-

tribution of which is controlled by the physical shape and magnetic properties of hub 40. The interrelation of the hub 40 and the fringing field, in turn, provides an axially increasing series of flux lines which, when crossed, interact with the electrons comprising the beam to further converge the beam.

For example, as the electron beam enters the magnetic field at the plane including point S in FIGURES 5 and 6, the beam is moving in a converging path with respect to the longitudinal axis of the tube. As shown in FIGURE 3, the travel of one such electron at the edge or boundary of the beam is represented by thick line 55 while thin lines 51 represent a portion of the magnetic lines of flux of the fringing field.

Owing to the outward fringing of the longitudinal field, a transverse component of magnetic field (radially inward) occurs at point S, FIGURE 5, which causes the electron beam to acquire an angular velocity. The electron, being a charged particle, is acted upon as it crosses the radially inward magnetic field and begins to spiral along path 56. As the electron crosses increasing values of flux, the angular velocity increases while the beam continues to converge exponentially to a certain value at the plane including ordinate point T, FIGURE 6, at which time Brillouin flow occurs.

That is, when the beam reaches point T, its diameter is such that the electrons comprising a segment of the beam are in dynamic equilibrium with the longitudinal magnetic field. The inwardly directed forces resulting from the longitudinal component of the magnetic field and the rotational velocity of the electrons cancel the outward forces of centrifugal force (of rotation) and the space charge effects of the electrons.

In FIGURE 5, the increasing values of flux crossed by the beam are depicted as lines 51 which, as shown, follow diverging paths in the region between the planes including ordinate points S and T and terminate on the adjacent surfaces of hub 40, the zone of termination being concentrated in the planes defined between the forward and rearward surfaces 52 and 53, respectively, of the pole piece 16. Thus, the composite of these flux lines, axial magnetic field B_a (FIGURE 4) is a gradually increasing field in this region and, as developed mathematically hereinafter, relates to the magnetic field sustaining Brillouin flow, B_m and the normalized exponentially decreasing radius of the beam as follows:

$$B_a = \frac{B_m}{R} \sqrt{1 - \frac{R}{R_o} e^{-\alpha z}} \quad (1)$$

where normalized quantities of this equation are related to actual quantities by the equations

$$R = \frac{r}{r_m} = 1 + (R_o - 1) e^{-\alpha z} \quad (2)$$

$$Z = \left(\frac{I_o}{2\pi\epsilon\sqrt{2\eta}(V_o)^{3/2}} \right)^{1/2} \frac{z}{r_m} = 174 \sqrt{P} \frac{z}{r_m} \quad (3)$$

and where

B_a is the axial magnetic flux density at any point along axis A—A

B_m is the flux density in Brillouin flow, given by the usual relationship

$$B_m^2 = \frac{\sqrt{2} I_o}{3 \pi \epsilon \eta^{3/2} V_o^{1/2} r_m^2}$$

or

$$B_m = \frac{830}{r_m} \left(\frac{I_o}{\sqrt{V_o}} \right)^{1/2} \text{ gauss for } r_m \text{ in cm.} \quad (4)$$

R is the normalized radius of the beam
 r is the actual beam radius at any point
 r_m is the radius in Brillouin flow
 R_o is the value of R at $Z=0$ (at point S in FIGURE 6)
 α is a constant given by

$$\frac{1}{[2R_o(R_o-1)]^{1/4}}$$

z is the actual axial distance from the zero magnetic field point (point S, FIGURE 6)

Z is the normalized axial distance

I_o is the beam current and V_o is the beam voltage (strictly speaking, the voltage on the beam axis)

ϵ is the permittivity of free space

η is the electronic charge-to-mass ratio

ρ is the beam perveance = $I_o/V_o^{3/2}$

Referring now to FIGURES 1 and 6, hub 40 which provides the field in accordance with Equation 1 is cylindrically shaped, having a forward end integral with planar pole piece 16 and an axis colinear with the axis A—A of beam travel. The inner surface 41 of the hub is reduced near rearward end 42 to form rearward and forward portions 43 and 44, respectively, with apertured extension lip 45 located therebetween for diminishing the magnetic field in the direction of the gun. The term "forward" is used, above, to describe the end of the assembly toward which the electrons travel after emission and refers to the right end of the hub 40 in FIGURE 1. Similarly, "rearward" designates the left end of the hub, as viewed.

Rearward portion 43 fits coaxially about the gun envelope of the tube to provide radial location of the tube relative to the axis of the solenoid and has a rearward portion which extends beyond the end of the envelope to shield the electron gun from stray magnetic fields. The rearward portion 43 also has an inwardly protruding step at its forward end which forms rearward surface 48 of lip 45 (FIGURE 6) which contacts the forward wall 47 of the envelope thereby locating the electron gun relative to the pole piece 16 of solenoid 11.

Centrally disposed within lip 45, aperture 46 provides a wall 49 snugly fitting about the elongated barrel 19 of the tube. In addition to preventing radial movement of the tube relative to the solenoid 11, the snug fit between the barrel and the wall of the aperture 46 also minimizes the amount of magnetic field which threads the cathode, as required to achieve Brillouin flow.

Coaxially located of the forward portion of the barrel of the tube to provide precise build-up of the axial magnetic field, forward portion 44 comprises an elongated cavity 50 of constant diameter having a forward end integral with pole piece 16. The forward portion 44 also has an inwardly protruding step at its rearward end which forms forward surface 54 of lip 45 (FIGURE 6) to provide a termination surface for the flux lines 51 (FIGURE 5), constituting the magnetic field as explained above.

When a voltage is applied to the windings of the solenoid, the distribution of the magnetic field in the forward portion 44 of hub 40 is as illustrated in FIGURE 5. If care is taken to eliminate magnetic saturation of the hub during tube and solenoid operations, the axial distribution of the gradually increasing field depends only on the diameter of the aperture 46, and the diameter and axial length of portion 44. However, note that dimensions of these parts relate to one another such that changes in one can be compensated by changes in the remaining terms to achieve the desired field build-up.

By way of example of the correct relationship of the parts, a hub having the following dimensions has been

constructed and tested with a traveling wave tube operating in X-band frequencies (8.0 to 12.5 kilomegacycles) in conjunction with a solenoid having a peak axial magnetic field of 3000 gauss; the assembly provided an axial magnetic field and flux distribution which converged the electron beam emanating from a cathode having a diameter of 0.470 inch and a density of 2 amperes per centimeter squared, to a final diameter of 0.0036 inch:

	Item—	Dimensions in inches
10	Portion 44:	
	Inside diameter -----	1.325
	Thickness -----	0.087
	Length -----	2.40
15	Lip 45:	
	Aperture 46 -----	0.350
	Thickness -----	0.060
	Portion 43:	
	Diameter -----	1.405
	Thickness -----	0.040
	Length -----	3.00

A plot of the normalized axial magnetic field provided by the above described hub 40 as a function of axial distance Z from the plane including the ordinate points S and T, FIGURES 5 and 6, is presented in FIGURE 4. In the plot, the ratio B_a/B_m is the normalized axial magnetic field where B_a is the axial magnetic field, and B_m is the axial magnetic field in Brillouin flow. Ordinate points S and T (FIGURE 5) are also shown to relate the normalized field strengths as a function of axial distance from the point of zero magnetic field on the axis of beam travel, i.e., point S within the aperture 46 of hub 40.

To further understand this field plot, consider a pole piece with no aperture therein and having a planar pole face. A plot of the magnetic field strength along the axis of symmetry A—A would be constant up to the pole face as shown by the dotted line 57 in the figure, whereat the magnitude of field would drop instantaneously from a given magnitude to zero, i.e., the field is a step function of distance Z along the axis A—A of the assembly. It is this type of magnetic field build-up upon which earlier gun designs were postulated for use in Brillouin focused traveling wave tubes.

However, in practice, step function characteristics of the idealized magnetized magnetic field could not be realized because of the leakage flux through the aperture of the pole piece. That is, the lines of force which would terminate on a plane pole face having an aperture terminate on or pass through the aperture. Some of the lines terminate inside the aperture, and some will crowd toward a plane situated adjacent the pole face. The net result is to change the field distribution so that the axial field plot is changed to the solid line curve 58 in FIGURE 5. This change in field distribution is compensated for by changes in the gun design which are usually done empirically.

However, in the instant invention, by forming of the hub 40 integral with the pole piece 16 and having the physical shape described above, the field is redistributed to the solid line curve 59. The curve illustrates that the axial magnetic field increases from $Z=0$ to $Z=3$ inches in a manner which converges the electron beam relative to the axis of beam travel and whereafter is constant for values of Z greater than 3 inches, to sustain the beam in Brillouin flow throughout the interaction region of the tube.

A fuller understanding of the operation of this invention may be obtained from the following mathematical analysis. Because of the particular type of magnetic and electrostatic fields to be discussed, polar co-ordinates will be used in their usual orientation to describe the electron path in the electrostatic and magnetic fields. MKS units also are used, except where specifically noted otherwise.

The radical force equation for an electron at radius r at the edge of the beam is

$$\ddot{r} = \frac{\rho r}{2} \eta + \dot{\theta}^2 - B_a \eta r \dot{\theta} \quad (5)$$

where $\ddot{r}$ is the second derivative of radius with respect to time and $\dot{\theta}$ is the angular beam velocity.

The first term on the right is the space charge force component, where ρ (a positive number) is the charge density of the beam (assumed independent of radius out to the edge of the beam), and η (a positive number) is the electronic charge-to-mass ratio. The second term on the right is the centrifugal force component, where $\dot{\theta}$ is the angular velocity of the electron. The last term on the right is the inward magnetic force on the electron (B_a and $\dot{\theta}$ being positive quantities).

The charge density can be expressed in terms of the beam current, beam voltage, and beam radius,

$$\rho = \frac{I_o}{\pi r^2 \sqrt{2\eta} V_o} \quad (6)$$

For shielded cathodes, the angular velocity is related to the axial magnetic field B_a by Busch's theorem,

$$\dot{\theta} = \frac{\eta B_a}{2} \quad (7)$$

we use 6 and 7 to rewrite 5

$$\ddot{r} = \frac{\eta^{1/2} I_o}{2\pi\epsilon\sqrt{2}V_o^{3/2}} \frac{1}{r} - \frac{\eta^2 B_a^2}{4} r \quad (8)$$

The time derivative in 8 can be converted into a space derivative yielding

$$2r'' = \frac{I_o}{2\pi\epsilon\sqrt{2\eta}V_o^{3/2}} \frac{1}{r} - \frac{\eta B_a^2}{4V_o} r \quad (9)$$

where r'' is the second derivative of r with respect to z .

Brillouin flow is obtained when the two terms on the right cancel, yielding Equation 1 for the Brillouin field B_m for radius r_m ,

$$B_m = \frac{830}{r_m} \left(\frac{I_o}{\sqrt{V_o}} \right)^{1/2} \text{ gauss for } r_m \text{ in cm.} \quad (10)$$

the normalized trajectory equation becomes

$$2R'' = \frac{1}{R} - B^2 R \quad (11)$$

where R is the normalized radius defined by

$$R = \frac{r}{r_m} \quad (12)$$

B is normalized axial magnetic field defined by

$$B = \frac{B_a}{B_m} \quad (13)$$

and Z is the normalized axial distance defined by Equation 3.

There are an infinite number of ways in which the flux density B can be made to build up. By the same token there are an infinite number of resultant trajectories, or solutions, of Equation 11 in the form of $R(Z)$. It is expedient to choose those trajectories of particular interest and solve Equation 11 for the $B(Z)$ required to yield those trajectories. In this manner the necessity of solving the differential equation is obviated, and completely analytical expressions are obtainable for $R(Z)$ and $B(Z)$. Choosing

$$R = 1 + (R_o - 1)e^{-\alpha Z} \quad (12)$$

where Z is the normalized axial distance, measured from

the zero magnetic point S (see FIGURE 6), R_o being the value of R at $Z=0$, and α a constant given by

$$\alpha = \frac{1}{\sqrt{2R_o(R_o-1)}} \quad (13)$$

the value of R in Brillouin flow being unity and therefore R_o being the radius convergence ratio, the normalized axial magnetic flux density B required is

$$B = \frac{1}{R} \sqrt{1 - \frac{R}{R_o} e^{-\alpha Z}} \quad (14)$$

Since

$$B = \frac{B_a}{B_m}$$

$$B_a = \frac{B_m}{R} \sqrt{1 - \frac{R}{R_o} e^{-\alpha Z}} \quad (15)$$

as presented above.

The foregoing analysis relates to an electron at the edge or boundary of the beam. Other electrons, nearer the axis of the beam, are subject to similar forces. They, however, cross less flux in the vicinity of the aperture and have lower transverse velocity in the uniform field and are subject to less total space charge force and less centrifugal force so they follow paths similar to those of the edge electrons but at smaller radii.

It should be understood that this invention in its broadest aspects is not limited to the specific example herein illustrated and described, and that the following claims are intended to include all changes and modifications within the spirit and scope of the invention.

What is claimed is:

1. An electron discharge device comprising a cylindrical vacuum envelope with one section having a diameter substantially greater than the diameter of an adjacent section and having a longitudinal axis, a cathode for producing a converging electron beam along the axis, said cathode being located in said one section in a region substantially free of magnetic field, a collector axially spaced from said cathode along the axis in the adjacent section for receiving the electron beam, a coaxially disposed magnetic field generating means axially spaced from said cathode toward said collector and adapted to produce a magnetic field for focusing the beam, and a coaxially disposed magnetic flux shaping hub member attached to the end of said magnetic field generating means proximate said cathode and extending therefrom over said cathode.
2. The electron discharge device according to claim 1 wherein said magnetic field generating means proximate said cathode and extending therefrom over said cathode, said magnetic flux shaping hub member having a cylindrical portion with a flat lip projecting radially inwardly therefrom immediately adjacent the junction of said sections of said cylindrical vacuum envelope, said inwardly projecting lip having a coaxially formed cylindrical aperture proximate the electron beam and said second section and dividing the interior of said cylindrical portion into a first cavity facing said magnetic field generating means and a second cavity containing the cathode, the transverse dimension of said first cavity being smaller than the transverse dimension of said second cavity.
3. The electron discharge device according to claim 1 wherein said magnetic field generating means comprises a solenoid.

9

portion immediately adjacent said magnetic field generating means.
